CLAIM

The ornamental design for a cover for volatile dispenser, as shown and described.

DESCRIPTION

In preferred embodiments the nature of this product is a cover for a plug-in type dispenser suitable for heating and thereby dispensing an active material such as an insect repellent, an insecticide, or a fragrance.

FIG. 1 is a left, top, front perspective view of a first embodiment of a cover for dispenser embodying our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof;

FIG. 8 is a left, top, front perspective view of a second embodiment of our new design;

FIG. 9 is a front elevational view thereof;

FIG. 10 is a left side elevational view thereof;

FIG. 11 is a right side elevational view thereof;

FIG. 12 is a top plan view thereof;

FIG. 13 is a bottom plan view thereof; and,

FIG. 14 is a rear elevational view thereof.

The broken line representations of vent holes, rear support structure, and top opening in the figures are for purposes of illustration only, and form no part of the claimed design.
